H. T. FOGG & J. J. FERRALL.
DISPLAY RACK.
APPLICATION FILED JULY 24, 1917.

1,291,463.

Patented Jan. 14, 1919.

UNITED STATES PATENT OFFICE.

HERBERT T. FOGG, OF EAST ORANGE, NEW JERSEY, AND JOHN J. FERRALL, OF VALHALLA, NEW YORK, ASSIGNEES TO NATIONAL BISCUIT COMPANY, OF NEW YORK, N. Y., A CORPORATION OF NEW JERSEY.

DISPLAY-RACK.

1,291,463.

Specification of Letters Patent.

Patented Jan. 14, 1919.

Application filed July 24, 1917. Serial No. 182,400.

To all whom it may concern:

Be it known that we, HERBERT T. FOGG and JOHN J. FERRALL, citizens of the United States, the former residing at East Orange, 5 in the county of Essex and State of New Jersey, and the latter residing at Valhalla, in the county of Westchester and State of New York, have invented certain new and useful Improvements in Display-Racks, of 10 which the following is a specification.

Our invention relates to display racks or stands wherein boxes containing crackers, or the like, may be placed so that the contents thereof will be effectively displayed. 15 Such boxes, intended for the use of retail merchants in displaying their wares, are often made with pivoted covers having glass panels or similar construction. In our improvement, however, the display rack 20 itself is provided with a cover or covers adapted to cover the open top or tops of a box or boxes mounted on the rack, which cover members contain glass panels so that the contents of the boxes may be seen. With 25 this construction the necessity of providing a large number of boxes with covers adapted for display purposes is done away with, different boxes, the contents of which are to be displayed, being placed on the rack and 30 covered by the cover members carried thereby, as desired.

The invention is best carried out by so mounting the cover members that the same will fit over the open tops of the boxes when 35 the latter are displayed while at the same time the cover members may readily be moved into a non-obstructing position in which they will remain, when a box is to be placed on or removed from the rack, or 40 when some of the contents of the box are to be removed. Preferably the cover members are pivotally mounted at their upper edges and are also arranged to slide back over 45 the top of the space designed to receive the boxes, out of the way when swung upwardly about the pivotal connection. Preferably also the supporting members for the boxes are so arranged as to hold the boxes at 50 an angle, with the upper open side of the box inclined at a forwardly and downwardly extending angle, so that the contents of the box may more readily be seen. Also preferably a

rack contains a number of units for receiving numbers of boxes arranged one above the other but somewhat offset, so that the lower 55 boxes are slightly in advance of the upper progressively, to enable the contents more readily to be seen.

In order that a clearer understanding of my invention may be had attention is hereby 60 directed to the accompanying drawings forming part of this application and illustrating certain embodiments of our invention.

In the drawings Figure 1 represents a side 65 elevation of a rack embodying our invention, Fig. 2 is a front elevation of the same, Fig. 3 is a partial enlarged vertical section taken on the line 3—3 of Fig. 2 and Fig. 4 is a 70 similar view showing a cover member in its raised and backwardly extending position.

Referring to the drawings the rack is 75 preferably made in skeleton form of pressed metal members and may comprise forward and back vertical members 1, 2 on each side. A vertical member 3 is also positioned on each side intermediate the forward and rear members 1 and 2. The forward and rear members on each side may be connected by horizontal members 4 and 5 at the bottom 80 and top respectively. The front members, 1, 1 may be connected by bottom and top transverse members 6 and 7 and the rear members 2, 2 may be connected by bottom and 85 top transverse members 6', 7'. The various frame members referred to are preferably light channels and may be welded or otherwise suitably secured together.

The rack illustrated is adapted to receive 90 six boxes, such as those shown at 8, 8, in two vertical rows of three each. Obviously, however, the racks may be made with different arrangements of spacings, or for the display of a single box only. In the construction 95 illustrated each box is received by a metal strip 9 which may be bent at a right angle, as shown, with the apex 10 at the bottom. The forwardly extending portion of sheet 9 is provided at its ends with upwardly extending portions 11, 11, the extreme ends of 100 the sheet being bent at right angles as shown at 12, 12. The upper and lower ends of the bent portions 12, 12 are secured to the webs of the adjacent vertical channel members 1

and 3. Similarly the rearwardly extending portions of the transverse strip 9 are provided at their ends with upwardly extending portions 11' and with right angle extensions 5 of the same 12', which are secured to vertical members 2 and 3. Obviously the strips 11, 12, 11', 12' may be made separate from the strip 9 and welded or otherwise secured thereto. The supporting means thus formed 10 are adapted to receive the boxes at an inclination with the open tops of the boxes inclined forwardly and downwardly as shown. The boxes are illustrated as mounted side by side in pairs with a space between 15 each pair.

It is deemed preferable to arrange the boxes vertically in offset relation, so that the lower ones will be forward of the upper, in order that the contents of all may more 20 readily be seen from above. This may be accomplished by arranging the support for the middle box in each vertical tier with its apex 10 in alinement with the intermediate vertical members 3 as shown, in which case 25 the support for the top box is arranged with its apex somewhat to the rear of the intermediate members 3, and the support of the bottom box is arranged with its apex somewhat to the front of members 3. With this 30 arrangement the flanges 11, 12, 11', 12' will be of unequal lengths, as shown, in order to extend into contact with the vertical members to which they are secured in each instance.

35 Cover members 13 are mounted on the rack in position to cover the open tops of the boxes displayed thereon, these cover members preferably being provided with glass panels 14. Each cover member is provided at its upper edge with a pivot member 40 15 which may comprise a rod about which the upper edge of the cover member is secured, with the ends of the rod extending somewhat beyond the side edges of the cover 45 member. The outer ends of each rod 15 are slidably mounted in tracks or slideways 16, which may in each instance be secured to the vertical members 3 and 2 on each side, and in the case of the uppermost unit, to the 50 members 2 alone. The slideways 16' which receive the inner ends of pivot rods 15 may be secured on both faces of metal sheets 17 which may have their upper and lower portions bent at an angle for securing the same 55 to the supporting strips 9 above the same. These slideways extend downwardly to the rear at an angle, as shown, and are preferably channel shaped. The upper flanges of the channels of these slideways are preferably 60 cut away at points slightly to the rear of the forward ends of the slideways as shown at 19, Fig. 3, to permit the insertion of the ends of rods 15 through the same into the slideways and the removal by the same 65 means of the cover members when it is de-

sired that the same should be entirely removed from the rack.

Preferably each cover member is provided with flanges 20 adapted to fit around the upper edges of a box 8 and a second slideway 21 is preferably mounted below each slideway 16 or 16' and secured in the same manner to members 3, 2 and 17. These latter slideways are preferably angular in cross section, as shown, and are adapted to 70 receive the marginal flanges of the cover, as shown at Fig. 4. When it is desired to uncover a box on the rack the cover is swung upwardly about pivots 15 until it is in position to clear the upper edge of the 80 box, when it is moved rearwardly into the position shown in Fig. 4, the pivots 15 sliding down the slideways 16 and 16' and the side flanges of the cover riding on the horizontal portions of the slideway 21. Preferably 85 a stop is provided for the cover in its rear-most position by mounting each slideway 21 on an angle which is slightly converging with the slideway 16 or 16' above the same so that the said flanges of the 90 cover member will become slightly wedged between slideways 16 and 21 and 16' and 21 when the cover member is in its rear-most position. It will thus be seen that positions 95 of stable equilibrium are provided for each 100 cover member both when the latter is in its operative or covering position and in its inoperative or non-obstructing rearward position. It is obvious that our invention is not strictly limited to the exact details of construction illustrated and described, but that a reasonable range of equivalents for such construction are included within our invention.

What we claim is:—

1. In a display rack, the combination of 105 end frame members; superposed box supports secured thereto to extend therebetween, each arranged to removably hold a pair of boxes side by side, with their tops 110 inclined forwardly and downwardly; outer track members secured to the end frame members, inclined rearwardly and downwardly above the spaces adapted to receive the boxes; inner track members, parallel to 115 said first named members, secured to the box supports above the same, intermediate the end frame members; cover members arranged to cover boxes on said supports, and pivot rods for said covers, having their outer and inner ends slidably mounted in 120 said outer and inner track members.

2. In a display rack, the combination of 125 a frame having supporting means arranged to removably hold a box with its top inclined at a forwardly and downwardly extending angle, a pair of superposed slide-ways secured to the frame, inclined rearwardly and downwardly above the space 130 adapted to receive the box, and a cover

member having pivots slidably mounted in one of said slideways, and arranged with side flanges to fit over the inclined top of a box in said space, when said pivots are at 5 the front of said slideway, said second slideway being adapted to receive the side flanges of said cover member when it is swung up and moved rearwardly.

This specification signed and witnessed this 19th day of July, 1917.
